UNITED STATES PATENT OFFICE.

JOHN P. WEIS, OF NYACK, NEW YORK, ASSIGNOR, BY MESNE ASSIGNMENTS, TO METROPOLITAN SEWING MACHINE CORPORATION, OF DOVER, DELAWARE, A CORPORATION OF DELAWARE.

SEWING-MACHINE DRIVING-SHAFT.

1,300,531.

Specification of Letters Patent. Patented Apr. 15, 1919.

Application filed June 15, 1916. Serial No. 103,729.

To all whom it may concern:

Be it known that I, JOHN P. WEIS, a citizen of the United States, residing at Nyack, in the county of Rockland and State of New York, have invented certain new and useful Improvements in Sewing-Machine Driving-Shafts, of which the following is a specification.

This invention relates to sewing machines, more particularly to the driving shafts thereof, the object of the invention being to produce a sewing machine having improved crank shafts, thereby to permit the manufacture of machines capable of high speed for either light or heavy work and which will also permit various attachments or mechanisms to be operated from either a top or bottom shaft of the machine.

In order to operate such mechanisms or attachments it is desirable that the top and bottom rotary shafts have a positive drive from one to the other and these rotary shafts must be properly balanced so that the machine will be free from vibration while operating at high speed.

In machines heretofore used with rotary top and bottom shafts the driving means connecting one shaft with the other was usually in the form of a belt, which has proven faulty, even though the bottom shaft was only used merely to drive the looper or bottom stitching mechanism. In other machines one or two connecting rods transmitted the motion from one shaft to the other, with the result that there was considerable lost motion at certain periods of each revolution and undue vibration. Still another class employed a vertical shaft with gearing to transmit the motion from the top shaft to the bottom shaft, which is unhandy in operation and difficult to lubricate and always had considerable lost motion at the gear connections.

In the present improvement all these disadvantages are done away with by the provision of a durable multiple top and bottom crank shaft having connections which will permit of their operation at the highest speed without vibration, noise or lost motion and one of the objects of the invention is to produce these shafts commercially at low cost, and the present improvement has been obtained only after considerable expense and experimentation.

These improved rotary shafts as arranged

for use in a sewing machine are provided with cranks and crank disks intermediate the ends of the shaft, thus leaving each end of the shaft free for driving connections, as for instance means for operating the needle bar from the top shaft on one end and for the hand wheel at the other end or top feeds or ruffling devices may be driven therefrom, while the bottom feed mechanism is operated from one end of the bottom shaft and the belt wheel connections at the other end thereof.

In the drawings accompanying and forming a part of this specification, Figure 1 is a front view of the improvement, the sewing machine frame being shown in dotted lines, illustrating the bottom shaft provided with feed driving means at one end and a belt wheel at the other, the top shaft with its needle driving mechanism at one end, and the hand wheel at the other, and the multiple connections extending from the cranks of one shaft to those of the other. Fig. 2 is a perspective view of one of the crank shafts showing the feed driving means and the belt wheel. Fig. 3 is a detail view of the various parts ready to be assembled to form the shaft shown in Fig. 2. Fig. 4 shows details of the crank pin and Fig. 5 is a detail view of the crank shaft connection and cap therefor.

Similar characters of reference indicate corresponding parts in the several figures of the drawings.

In the drawings the sewing machine frame 1 has suitable bearings 2 and 4 for the bottom rotary shaft 3. The end of this shaft carries a belt wheel 6 shown in section for rotating this bottom shaft. This wheel and its belt operate within a housing 7 to protect the operator and the work from the wheel and its belt. The top rotary shaft 8 operates in bearings 9 and 11 and is provided with a hand wheel 12. By having the hand wheel separate from the belt wheel a material advantage is obtained because the hand wheel is grasped many times a day in operating the machine and in this improvement the belt does not interfere in any way. A needle bar 13 is operated by the pitman 14 from the crank disk 15 secured to the end of the top shaft 8.

As the crank portions of the top and bottom shafts are identical, a description of one will suffice for both. Shaft or shaft por-

tion 3 for instance is drilled as at 16 to receive a stem 17 of the feed driving means. This stem is drilled and tapped as at 18 to receive a screw 19, the end of which screw 5 impinges against one wall of the hole 16, while the head 21 acts as a key in the hole 22 of the shaft 3. Grooves 23 are provided for positively positioning the eccentric for operating the bottom stitch and feeding 10 mechanism. The shaft 3 is reduced as at 24 and is knurled or otherwise roughened as at 25, see Fig. 3. Four disks 26, 26', 26'', 26''' are provided of equal thickness and diameter. One as 26 is drilled centrally as 15 at 27 to receive the end 24 of the shaft 3, which is pressed therein up to the shoulder 28 of the shaft 3. The knurled or roughened surface of the shaft end prevents the disk from turning on the shaft. A hole 29 is also provided in the disk 26 to receive the end 30 of the crank pin 31, while the opposite end 32 of the pin is forced into the hole 33 of the disk 26'. This hole 33 is also 20 drilled off center of the disk to correspond with the hole 29. The distance that these crank pin holes are located from the center may vary to suit the conditions under which the shafts are used, but each crank pin of each shaft must be necessarily the same distance 25 from the center in order to operate properly. The disk 26' is also drilled as at 35 to receive the end 36 of a crank pin 37, while the end 38 is forced into the hole 39 of the disk 26''. A hole 41 in the disk 30 26'' receives the end 42 of the crank pin 43, while the end 44 of this pin is forced into a hole 45 of the disk 26''''. This last disk 26''' is drilled centrally as at 47 to receive the end 48 of the shaft 5. The reduced ends 35 of the crank pins and shafts respectively are usually knurled or roughened to insure a tight positive driving fit in each of the respective holes. The crank pins when assembled in the disks are located or spaced 40 120 degrees from one another. In order that these shafts may be used at high speed, it is practically necessary to have them hardened. In the hardening process integral shafts of the length required become 45 distorted or warped and before they can be assembled they must be straightened, but by making them in the manner shown much better results are obtained in many ways.

In assembling a shaft made in the manner 50 described suitable jigs and fixtures are provided to facilitate the work. According to one way of assembling the shaft the shaft 3 is placed in a jig and the reduced end 24 is forced into the hole 27 of its disk. Next the end 30 of the pin 37 is forced 55 into the hole 29, then the opposite end 32 of this pin is forced into the hole 33 of the disk 26' and next the end 36 of pin 37 is forced into the hole 35. Then the end 60 38 of this pin 37 is forced into the hole 39 of disk 26'', then the end 42 of pin 43 is forced into the hole 41 and the end 44 into the hole 45 of disk 26''''. Then the end 48 of shaft portion 5 is forced into the hole 47 of the disk 26''' thus completing 70 the assembling of the shaft. It is found in practice however, that the preferable way of assembling the shaft is to first press the two center disks together on its connecting stud or pin and then thereafter assemble each 75 end disk in sequence and then the short shaft 5 into its disk and then the longer shaft 3 into its disk, the pressure exerted in assembling the several parts being so great that they are united in such an efficient 80 manner that they are permanently held together, and this without the necessity of any separate fastening pins, nuts or bolts. Then the shaft is ground and to facilitate the grinding operation, each crank pin is provided 85 with a reduced portion 49, see Fig. 4, leaving the crank portion 50 full diameter, so that the grinding wheel can enter between the disks as at 51 to do this work without leaving a fillet or running close to 90 the disks, which would interfere with the connections. The shaft connections or connecting rods 52 are preferably made tubular, having the end bearings 52 and 53 secured thereto. The cap 54 is likewise drilled at 95 55 to receive a wick 56 to conduct the lubricant from one shaft down through the tube to the other.

By reason of the location of the crank pins at 120 degrees from one another, the 100 length of each connection 52, that is to say, from the center lines 57, is exactly the same. It has been demonstrated that with this organization of shafts and connections there is practically no strain on the screws, 105 which hold the caps 54 in place so that the machine will actually operate without the caps when the top part of the sewing machine frame is placed upon the base and secured thereto in the usual manner. The 110 machine may be operated indefinitely without injury to the operating mechanism thereof, therefore the location of the multiple cranks is important and it will be seen by viewing Fig. 1 that the shaft portion 5 115 operates in its bearing close to the disk 26''' while the shaft 3 operates in its bearing 1 close to the disk 26, while the upper shaft portion 10 operates in a similar bearing close to a similar disk. The shafts are well 120 supported to prevent springing thereof, which overcomes the lengthwise strain of the connections that causes noise and lost motion if they were otherwise located or should the machine be operated without the 125 connection caps in place. Furthermore unless vibration is eliminated such vibration would extend from one shaft to the other and cause considerable wear, necessitating many replacements.

I claim as my invention:—

1. A crank shaft comprising two spaced and alined shafts, an end crank disk secured on the adjacent end of each shaft, 5 each of said disks having a wrist pin aperture, a plurality of intermediate crank disks having two wrist pin apertures, and wrist pins secured and held in said apertures by a tight fit.
- 10 2. A crank shaft comprising two spaced and alined shafts, an end crank disk secured on the adjacent end of each shaft by a tight fit, each of said disks having a wrist pin aperture, a plurality of intermediate crank disks having two wrist pin 15

apertures, and wrist pins secured and held in said apertures by a tight fit whereby said disks are connected solely by insertible wrist pins located at spaced intervals relatively to each other around the crank disks, each of said wrist pins having reduced portions and also having together with the ends of the shafts reduced roughened portions of less diameter than said first reduced portions.

Signed at Nyack, in the county of Rockland and State of New York, this 13th day of June, 1916.

JOHN P. WEIS.
